UNITED STATES PATENT OFFICE.

OTTO HEINIGKE, OF NEW Utrecht, NEW YORK, ASSIGNOR TO THE HARTFORD CARPET COMPANY, OF HARTFORD, CONNECTICUT.

DESIGN FOR A CARPET.

SPECIFICATION forming part of Design No. 14,873, dated March 11, 1884.

Application filed January 28, 1884. Term of patent 3½ years.

To all whom it may concern:

Be it known that I, OTTO HEINIGKE, of New Utrecht, in the State of New York, have invented a new and original Design for Carpets, 5 of which the following is a specification, reference being had to the accompanying photograph, which forms a part of the same.

The invention relates to a design to be worked into or upon surfaces, such as carpets or similar 10 fabrics; and it consists in the novel configuration and grouping of figures herein specifically shown and claimed.

The accompanying photograph is a face view 15 of a carpet showing my new design.

The features of the design are the prominent panel-borders and the large skeleton-leaf forms.

The panel-borders are various, and are richly ornamented with small geometric, scalloped, and Greek-letter work. The panels are ornamented by large skeleton leaves, of which 20 three appear in the photograph, each of these large leaves bearing flower ornamentations of its own. The design is loosely filled in with flower-sprays and with various small crystal shapes and geometric figures. 25

I claim—

The design for a carpet, substantially as shown and described.

OTTO HEINIGKE.
